UNITED STATES PATENT OFFICE.

WILLIAM C. BAKER, OF NEW YORK, N. Y.

STEAM-BOILER.

SPECIFICATION forming part of Letters Patent No. 590,471, dated September 21, 1897.

Application filed February 8, 1897. Serial No. 622,461. (No model.)

To all whom it may concern:

Be it known that I, WILLIAM C. BAKER, a citizen of the United States, residing in the city, county, and State of New York, have 5 invented an Improvement in Steam-Boilers, of which the following is a specification.

In Letters Patent No. 537,177, granted to me April 9, 1895, a water heating apparatus is represented in which there are upper and 10 lower pipes crossing the fire-chamber and connected by vertical pipes that are larger at the upper part than at the lower. These pipes were originally made by me and screwed together and were employed in a fire-chamber 15 with the fuel closely surrounding and rising above the tubes.

I find that sections can be advantageously made with upper and lower tubes and intermediate pipes that are largest at the top, and 20 cast in iron or steel, copper, or bronze, and placed transversely of the fire-chamber over the grate-bars in connection with a division separating the fire-chamber from a flue below a steam-boiler, the upper ends of the tubes 25 being connected to such steam-boiler; and I employ return circulating-pipes from the lower part of the boiler to the sections at one end, and the steam as it is passed away from the boiler is carried upward to such 30 perheaters formed of one or more boiler-sections constructed as aforesaid, such sections being placed in the flue that takes away the products of combustion; and I prefer to make use of inclosing brickwork and a return-flue 35 above the boiler, so that the products of combustion from the fire-chamber pass off at the rear end and return beneath the boiler and around the return circulating-pipes and then pass away over the boiler and descend around 40 the superheating-sections before ascending to the chimney or place of final delivery.

In the drawings, Figure 1 is a perspective illustration showing the parts of the boiler with the brickwork inclosure broken open. 45 Fig. 2 is a cross-section of the boiler and heating-tubes; and Fig. 3 shows the back end of the boiler, the descending flue, superheater, and the base of the chimney.

The fire-door A and grate-bars B are to be 50 of any desired character, and these are set on brickwork C, which incloses the ash-pit. The boiler-sections D are made with a lower tube

4 and an upper tube 5, with intermediate vertical tubes 6, which are largest at the upper ends, where they open into the upper tube 5, 55 and smallest at the lower ends, where they open into the lower tube 4, and these boiler-sections are preferably of cast metal of sufficient strength to withstand the pressure, and at one end of each tube 4 is a cap 7, by 60 the removal of which access is given to the tube for removing any sediment.

The boiler E is preferably cylindrical and there are coupling connections F between the upper end of the upper tube 5 and the boiler, 65 such coupling connections advantageously opening into the lower part of the boiler at one side thereof, and there are return-pipes G, connected by elbows 8 to the under side of the steam-boiler E and by elbows and vertical portions 9 with the back ends of the lower tubes 4, so that the boiler-sections and the lower part of the boiler being filled with water the heat will act to cause such water to rise through the tubes 6 and upper tube 5 75 into the boiler and return through the elbows 8, pipes G, and vertical tubes 9 to the back ends of the lower tubes 4.

The boiler may be of any desired length, and the number of boiler-sections D may be 80 greater or less, according to the capacity required of the boiler, and these boiler-sections are advantageously placed as near each other as consistent with the proper space for bolts and connections.

The side walls 10 are built up and preferably closed in at the offsets 11 to the sides of the boiler E, and there is a partition H of fire-brick resting upon the upper tubes 5 of the boiler-sections and extending from the 90 front wall 12 of the inclosure to near the back wall 13, so that the products of combustion will pass to the rear and ascend between the end of the partition H and back wall 13, and such products of combustion will return over 95 the partition H through the flue beneath the boiler and pass up between the front wall 12 and the end of the boiler F and return over the boiler through a flue 20, formed beneath the arch I, and will descend behind the back 100 wall 13 in the flue that there is between such back wall and the wall 14 at the base of the chimney J and will ascend into such chimney or final escape-flue.

The steam from the boiler E is to be taken off by any suitable pipes. I have represented the pipes K as rising from the boiler and extending to the rear and connecting to the 5 superheaters formed of the boiler-sections D', standing in reverse positions and connected at their ends, the escape for the steam being from one end of the lower superheating-section.

- 10 It will now be understood that the fuel is to be supplied upon the grate-bars B and either close to or surrounding the lower portions of the boiler-sections D, and the products of combustion rising from the fuel pass between 15 the vertical tubes 6 and below the upper tube 5 of the boiler-sections, and in consequence of the return-bends 15 at the ends of the upper tubes 5 the rising column of hot water is easily led back over the partition H and passes 20 into the boiler, and the return-bends 15 and the coupling connections F are exposed to the action of the heat in the flue between the partition H and the under side of the boiler, and the return-pipes G are also exposed to the 25 action of heat, so that most of the heat is absorbed and transferred to the water in the boiler-sections and in the boiler, and what heat may escape in the flue 20 between the top of the boiler and the arch I serves to 30 superheat the steam in the top of the boiler, and such steam is further superheated by the action of the descending products of combustion in the flue between the walls 13 and 14, so that the steam is dry and passes away with 35 out water of condensation from the superheating-pipes to the engine or to radiators or other heating or power devices.

The inclosing fire-brick may be provided with stay-bars or angle-irons of any desired 40 character.

In boilers that are used for heating purposes I find it advantageous to employ a safety-vent plate at L similar to that shown in my Patent No. 473,722, and there is a chest or box 45 surrounding the body of the safety-vent with a pipe M, leading to the ash-pit, so that in case the pressure becomes excessive and the safety-vent plate gives way the steam passes by the pipe M into the ash-pit in sufficient 50 volume to deaden the fire, or the steam-pressure may act upon an alarm or other device for calling attention to the fire of the boiler. Gage-tubes and cocks should be provided for the boiler, as usual.

55 This apparatus is applicable to the generation of steam for an engine or for any heating apparatus, and it may also be used for heating the water in any hot-water heating apparatus.

60 The top part of the boiler E acts as a superheater in consequence of the flue passing over the same, and the steam descending in the superheaters is raised to the temperature of the escaping gases, or nearly so.

65 There may be a mud-drum N below the back ends of the pipes 4 and connected with them by vertical pipes 17, so that sediment may

pass into this mud-drum and be blown off periodically.

I claim as my invention—

70 1. The boiler-sections each formed with an upper and a lower tube connected by intermediate vertical tubes that are largest at the top and open into the upper tube and smallest at the bottom and open into the lower tube, 75 the same being cast integral and the lower tube having a removable cap at one end and the upper tube having a return-bend in combination with a boiler above the boiler-sections and intermediate coupling connections 80 between the return-bends and the boiler, and return-pipes between the boiler and one end of the lower pipe in each boiler-section, substantially as set forth.

85 2. The combination with a boiler, of a row of tubular boiler-sections below the boiler, each boiler-section having an upper and a lower tube and intermediate vertical tapering tubes, a return-bend and coupling connection between the upper tube of the section 90 and the boiler and return circulating-pipes between the boiler and the back end of the lower tube in each boiler-section, substantially as set forth.

95 3. The combination with a boiler, of a row of tubular boiler-sections below the boiler, each boiler-section having an upper and a lower tube and intermediate vertical tapering tubes, a return-bend and coupling connection between the upper tube of the section 100 and the boiler and return circulating-pipes between the boiler and the back end of the lower tube in each boiler-section, a partition of refractory material above the upper tubes of the boiler-sections and below the boiler to 105 confine the products of combustion around the tubes of the boiler-sections and allow them to pass away at the back end and return under the boiler, substantially as set forth.

110 4. The combination with the steam-boiler and the inclosure for the fire-chamber and flues, of an arch over the boiler inclosing an upper flue, grate-bars below the fire-chamber, boiler-sections crossing through the fire-chamber, each boiler-section having a lower 115 tube and an upper tube and vertical tapering connecting-tubes and coupling connections between the sections and the boiler, return circulating water-pipes and a partition above the upper tubes of the boiler-sections and 120 separating the fire-chamber from the flue below the boiler which contains the coupling connections and the return circulating-pipes, substantially as set forth.

125 5. The combination with the steam-boiler and the inclosure for the fire-chamber and flues, of an arch over the boiler inclosing an upper flue, grate-bars below the fire-chamber, boiler-sections crossing through the fire-chamber, each boiler-section having a lower 130 tube and an upper tube and vertical tapering connecting-tubes and coupling connections between the sections and the boiler, return circulating water-pipes and a partition above

the upper tubes of the boiler-sections and separating the fire-chamber from the flue below the boiler which contains the coupling connections and the return circulating-pipes,
5 a flue between the back walls receiving the products of combustion from the flue over the boiler and superheating-sections similar to the boiler-sections and standing in reverse

positions within the vertical flue, and steam-pipes connecting with such superheaters, substantially as set forth.

Signed by me this 3d day of February, 1897.

WM. C. BAKER.
